PROCESS FOR CHLORINATING
CHLORPROPANE

James S. Sconce, David S. Rosenberg, and Arnold N. Johnson, Niagara Falls, N. Y., assignors to Hooker Electrochemical Company, Niagara Falls, N. Y., a corporation of New York

No Drawing. Application December 8, 1944,
Serial No. 567,314

3 Claims. (Cl. 204—163)

1

Our invention relates more particularly to promotion of organic halogen substitution reactions, especially when it is desired to carry the reaction further than it will readily go under ordinary conditions. An example of such a reaction is afforded by photochemical chlorination of paraffinic hydrocarbons to complete replacement of the hydrogen by chlorine. It is known that such reactions are retarded or inhibited in presence of oxygen or the resulting oxygenation products. One of the objects of the invention is to promote the speed and completeness of the reaction and carry it further than would otherwise be practicable under such conditions.

The partial chlorination of hydrocarbons of all kinds is comparatively easy. The complete chlorination of hydrocarbons is much more difficult. Methane and ethane are about the only hydrocarbons that have hitherto been fully chlorinated on a commercial scale.

We will describe our process with particular reference to production of octachloropropane. This may be produced without great difficulty by chlorination of hexachloropropylene. However, hexachloropropylene is a valuable product in itself and it is one of the objects of the present invention to produce octachloropropane directly from propane.

Propane is derived from natural gas and may be chlorinated, starting in vapor phase, to produce mixtures up to the heptachlor, which are liquid at ordinary temperatures. These mixtures may then be further chlorinated to octachloropropane in liquid phase. This has been done, on a small scale, by various processes, all of which are unsatisfactory as to cost or yield or both. One of the objects of the present invention is to produce octachloropropane by a practicable process, suitable for operation on a commercial scale, so as to render the produce available to the arts.

One way in which octachloropropane has hitherto been produced on a small scale is by first chlorinating to the heptachlor and then dehydrochlorinating by means of caustic soda to hexachloropropylene which, being unsaturated, may be chlorinated without great difficulty to octachloropropane. This process is obviously too complicated. Furthermore, the production of heptachloropropane is itself difficult and the yield poor.

2

Mixtures of chloropropanes have been further chlorinated in liquid phase to a mixed product containing a minor proportion of octachloropropane by the use of a liquid chlorinating agent, such as iodine trichloride, antimony pentachloride, etc., or by the use of liquid chlorine under high pressures, in both cases at about 200° C. At this temperature there is much splitting of the molecule to carbon tetrachloride and hexachloroethane. These mixtures have also been chlorinated with gaseous chlorine at atmospheric pressure by the aid of very powerful actinic light, likewise at about 200° C. As before, there is much splitting of the molecule; also the intensity of the required light limits the size of the chlorination units, and the time cycle is excessive.

We have now succeeded in chlorinating mixtures of chloropropanes, having a specific gravity of 1.70 to 1.76, corresponding to a mixture of pentachlor- to heptachloropropane, by means of gaseous chlorine, and with the aid of actinic light of moderate intensity (1,200 watts for a 500 gallon reactor) at a moderate temperature and pressure (90° to 150° C. and 10 to 100 lbs. per sq. in. respectively), with an almost quantitative yield of octachloropropane.

These results have been rendered possible by a simple treatment of the chloropropane mixture, prior to further chlorination thereof, with a basic substance, such as the alkali metal and alkaline earth hydroxides and alkali metal carbonates, in such small quantities and under such conditions as to cause no appreciable dehydrochlorination of the material or other modification of its molecular structure. This treatment is effected by agitating the liquid chloropropane mixture with a small quantity of the alkali, amounting to one or two per cent by weight, at 35° to 90° C., for from 30 to 60 minutes, and then filtering out the solids from the liquid material, and thus removing any solid or colloidal suspended contaminants. Without this treatment the further chlorination of the chloropropane mixture, under the conditions as to temperature and pressure indicated above, is impracticable, if not impossible. After this treatment, however, the chlorination proceeds rapidly and smoothly to substantial completion, with an almost quantitative yield, as above stated.

The product obtained by our process as above

described analyzes within one per cent or less of the chlorine content corresponding to octachloropropane made by the process of the prior art. This is within the limits of error of the best known methods for determination of chlorine in organic compounds.

Octachloropropane, such as may be produced by chlorination of hexachloropropylene, is a white crystalline material melting at 160° C. and theoretically containing 88.7 per cent chlorine. It may be readily ground to a powder. Our product contains 88+ per cent chlorine by analysis and melts at 120° to 155° C. It has a tough waxy consistency and cannot be ground. It gives off only 0.02 to 0.04 per cent of its chlorine when maintained at 140° C. for 16 hours. This is an evidence of a high degree of stability as compared with chlorinated hydrocarbons in general, some of which would give off 30 per cent of their chlorine under similar conditions.

Why our octachloropropane product should have physical characteristics different from those of the prior art product, is not at present known. At any rate, the different physical properties of our product, as compared with those of the crystalline product, give it greatly enhanced value. For example, it is firmly adherent to smooth surfaces. It is compatible with lubricating oils and is itself an excellent lubricant for such surfaces as those of plug cocks and bearings exposed to highly corrosive chemicals, such as chlorine, HCl, HF, HNO₃, H₂SO₄, etc. It is also an excellent plasticizer for natural and synthetic resins, forming therewith a great variety of compositions suitable for impregnation and coating, for the purpose of fireproofing and weatherproofing.

Our octachloropropane product also forms with other chlorinated hydrocarbons a whole series of compositions having useful properties. In particular it forms with hexachlorethane a series of compositions which are unique in that, although fully chlorinated, they are nevertheless of a tough waxy consistency, being in this respect entirely unlike compositions produced by blending hexachlorethane with pure crystalline octachloropropane.

Example I

1150 lbs. of chloropropane mixture having a specific gravity of 1.73 corresponding to a mixture consisting mostly of pentachloroheptachloropropane, were agitated with 15 lbs. of Ca(OH)₂ at 90° C. for one hour and the material passed through a filter press. The filtered material weighed 1110 lbs. This was chlorinated under actinic light as follows:

Duration	Temperature	Pressure	Chlorine Supplied
Hours	°C.	Lbs. gage	Lbs.
0-6	90-140	28-32	300
6-12	129-136	29-42	310
12-18	124-139	27-38	240
18-24	130-139	29-36	235
24-30	130-138	30-34	150

The product was blown for 15 minutes with CO₂ to remove dissolved HCl and Cl₂. When cast 70 and cooled into a slab and dropped onto a hard surface it emitted a metallic clink. It could not be ground. It was substantially colorless and of a waxy consistency, analyzed 88+ per cent chlorine, and had a first crystal point of 143° C., a 75

last crystal point of 152° C. and a boiling point of 259° C. The product weighed 1,249 lbs. which on the basis of its analysis represented a yield of 94.2 per cent of theory.

5 A determination of molecular weight, in accordance with the Beckmann theory that 1 gram molecule of solute depresses the freezing point of 1,000 grams of benzene 5.12° C., showed that the molecular weight of our product was 314, which 10 corresponds closely to octachloropropane monomer, with practical exclusion of its polymerization derivatives.

Example II

15 The product of Example I was blended with hexachlorethane in various proportions ranging from 20 to 200 per cent of its weight of the latter, and the cloud points determined. It was found that the mixture containing 20 per cent of hexachlorethane had a cloud point of about 108° C., which was the lowest cloud point obtained. This composition was transparent, tough and extremely flexible. When melted and poured on glass it could not be chipped or scraped off or otherwise removed without the aid of heat or a solvent. It proved to be inert to aqueous HF glass etching solution. When rolled out in a sheet it was found to have considerable tensile strength and elasticity, and when cut into strips these could be twisted and tied into knots.

Example III

20 Two identical portions of chloropropane, having the same specific gravity as in Example I, were air blown to saturation with oxygen. One was given the alkali treatment, as in Example I. The other was not treated. Both were then chlorinated to octachloropropane, likewise as in the first example. The alkali treated portion required 26 hours and 1,022 lbs. chlorine per pound of product. The other required 55 hours and 1,511 lbs. chlorine per pound of product. This shows that the alkali treatment not only reduces the time of the reaction to about one-half, but 25 also greatly increases the chlorine efficiency.

Example IV

25 Two identical portions of chloropropane, having a specific gravity of 1.70, were both chlorinated to octachloropropane, one with practically oxygen free chlorine and the other with chlorine containing a trace of oxygen (about 0.1 per cent). The first required 56 hours and consumed 1,148 lbs. of chlorine per pound of product. The second required 75 hours and consumed 1,545 lbs. of chlorine per pound of product. This shows that oxygen in the chlorine has the same inhibiting effect as oxygen in the hydrocarbon.

30 Since the reaction is exothermic, the temperature of the reaction mixture at a given stage of the reaction, under given conditions as to radiation of heat, etc., is a function of the rate of reaction. The effect of the alkali treatment upon the rate and completeness of absorption of the chlorine, can therefore be likewise demonstrated by noting the temperature of the reaction mixture as the reaction proceeds.

Example V

35 500 c. c. of dichlorethane (ethylene dichloride) were air blown for 15 minutes to saturate the liquid with oxygen. The sample was then divided into two equal portions. One part was given a treatment with a 10 per cent solution of NaOH for 30 minutes and dried. Each portion was

placed in a 250 c. c. flask and the two flasks placed in a constant temperature bath maintained at 10° C. Both portions were chlorinated at atmospheric pressure by gaseous chlorine introduced at the same rate; namely, 280 c. c. per minute under the same conditions as to actinic light, and the change in temperature with lapse of time noted.

The results were as follows:

Time Minutes	Temperature	
	Untreated Portion	Treated Portion
10	59.5	59.5
11	59.5	59.5
12	59.5	60
13	59.3	60
14	59.2	60
15	59.2	60
16	59.0	60
17	59.0	60.5
18	59.0	60.7

The results show that at 7 minutes both portions were at the same temperature. After 9 minutes the portion that had been given the alkali treatment had forged ahead. After 15 minutes, the temperature of the untreated portion was falling. This is normal; but at the same time the temperature of the treated portion was rising. This is a wholly unpredictable result.

Example VI

The experiment of Example V was repeated with a chlorheptane mixture having a specific gravity of 1.527, corresponding to a chlorine content of 70.5 per cent. After 23 minutes this showed the same phenomena, namely a falling temperature in the case of the portion that had not had the alkali treatment and an anomalous rising temperature in the case of the treated sample.

Example VII

The experiment of Example V was repeated with paraffine wax. In this case one portion of the molten wax was given the alkali treatment before either had been chlorinated at all, i. e., while both were still free from dissolved HCl. After 125 minutes the untreated portion showed a temperature of 77° and its specific gravity had increased from 0.776³⁰ to 0.984³⁰. At the same stage the treated portion showed a temperature of 78° C. and its specific gravity had increased to 1.001³⁰. This is believed to prove not only that the benefit derived from the alkali treatment holds for long chain as well as for short chain paraffinic hydrocarbons; but also that it is not due merely to neutralization of HCl.

Example VIII

The experiment of Example V was repeated with isopropyl adipate. The same anomalous and unpredictable result was obtained. That is to say, after 9 minutes the untreated portion was at 62° C. and the treated portion at 65° C. This shows that the alkali treatment promotes chlorination even when there is oxygen in the molecule. In this case, the reaction was found to be chiefly a substitution of chlorine for hydrogen in the isopropyl group.

Example IX

The experiment of Example V was repeated with isopropyl benzoate. The results were the same as before. That is to say, after 6 minutes

the untreated portion showed a temperature of 59° C. and the treated portion a temperature of 62° C., proving that the beneficial effect of the alkali treatment is not limited to paraffinic compounds. As in Example VIII, the reaction was principally a substitution of chlorine for hydrogen in the alkyl group.

While we have illustrated our process by specific example, we do not wish to be limited thereto, as our process is evidently applicable to halogenation of organic materials in general, the halogenation of which is retarded in presence of oxygen other than oxygen that may be in the molecules of the material itself, and the molecular structure of which is not modified by the treatment preparatory to halogenation. Neither do we wish to be limited to photochemical halogenation, as our process is applicable to analogous heat or infra-red activated or chain mechanism halogenation of organic materials within the above defined category which are susceptible of halogenation under such conditions. Likewise, we do not wish to be limited to the alkalis specifically mentioned or used in the example, as any basic reacting substance is more or less effective in our process, when the conditions of the reaction, i. e., as to the reactivity and concentration of the basic reacting substance, temperature at which the treatment is carried out, time of treatment, etc., are such that there is little or no dechlorination, dehydrochlorination or other modification of the molecular structure of the material.

We claim as our invention:

1. The process for chlorination by substitution of chloropropane, by means of gaseous chlorine, when one of the reagents contains free oxygen, which comprises contacting the liquid organic material with 1 to 2 per cent of its weight of a material of the group consisting of the alkali metal and alkaline earth hydroxides and alkali metal carbonates, for at least 30 minutes; removing the alkaline material and any suspended solids from the organic material; and passing gaseous chlorine into the organic material, at 90° to 150° C. and under a pressure of 10 to 100 pounds per square inch gauge, under actinic light effective in catalyzing the reaction, until the reaction has gone as far as practicable.

2. The process for chlorination by substitution of chloropropane mixtures having a specific gravity of 1.70 to 1.76, by means of gaseous chlorine, when one of the reagents contains free oxygen, to produce octachloropropane, which comprises contacting the liquid organic material with 1 to 2 per cent of its weight of a material of the group consisting of the alkali metal and alkaline earth hydroxides and alkali metal carbonates, for at least 30 minutes; removing the alkaline material and any suspended solids from the organic material; and passing gaseous chlorine into the organic material, at 90° to 150° C. and under pressure of 10 to 100 pounds per square inch gauge, under actinic light effective in catalyzing the reaction until the reaction has gone as far as practicable.

3. The process for chlorination by substitution of chloropropane mixtures having a specific gravity of 1.70 to 1.76, by means of gaseous chlorine, when one of the reagents contains free oxygen, to produce octachloropropane, which comprises contacting the liquid organic material with 1 to 2 per cent of its weight of calcium hydroxide at 35° to 90° C. for 30 to 60 minutes;

removing the alkaline material and any suspended solids from the organic material; and passing gaseous chlorine into the organic material, at 90° to 150° C., under a pressure of 28 to 34 pounds per square inch gauge, under actinic light effective in catalyzing the reaction until the reaction has gone as far as practicable.
